UNITED STATES PATENT OFFICE.

FREDERICK E. STRASBURG, OF RUMFORD FALLS, MAINE, ASSIGNOR TO
CONTINENTAL PAPER BAG COMPANY, A CORPORATION OF MAINE.

PAPER-BAG MACHINE.

SPECIFICATION forming part of Letters Patent No. 787,648, dated April 18, 1905.

Application filed April 18, 1904. Serial No. 202,987.

To all whom it may concern:

Be it known that I, FREDERICK E. STRASBURG, a citizen of the United States, residing at Rumford Falls, in the county of Oxford and State of Maine, have invented certain new and useful Improvements in Paper-Bag Machines, of which the following is a specification.

This invention relates to paper-bag machines, and more particularly to that class of paper-bag machines for automatically making square-bottom paper bags from tucked-paper tubing.

My improvement relates particularly to those parts of such a paper-bag machine as are provided to fold one end of a section of tucked-paper tubing into the diamond form.

In the drawings accompanying this specification, Figure 1 is a side elevation, partly in section, of so much of a paper-bag machine of the class specified as will illustrate the general features of my improvement. Fig. 2 is a side elevation, also partly in section, illustrating, on an enlarged scale, one form of the creasing means and the severing means of my improvements. Fig. 3 is a plan view of the creasing-rolls shown in Fig. 2 looking in the direction of arrow *d* in said figure. Fig. 4 is a sectional view on line *c c* of Fig. 3, illustrating the operation of the creasing mechanism. Figs. 5 to 14, inclusive, are a series of front and end elevations, respectively, some of which are partially in section, illustrating successive positions of the diamond-folding mechanism. Fig. 15 is a plan view of the tube-severing mechanism.

Similar characters of reference designate like parts throughout the several figures of the drawings.

The paper-bag machine in which I have chosen in the present instance to embody one form of my improvement, and which may be its preferred form, may comprise side frames, as 3, in which may be supported the various parts of the paper-bag machine embodying my improvements. Power may be communicated from some suitable source of power to shaft 5 and through gear 6, fast thereon, to

the various parts of the machine. From gear 6, through the train of gears 7 to 12, inclusive, power is conveyed to gear 13, fast to shaft 15, to which shaft is also fixed lower creasing-roll 17. From gear 10 power is communicated to gears 19 20, fast on the shafts of feed-rolls 21 22, respectively. Said gearing is so proportioned and arranged as to drive rolls 17 18 and 21 22 at equal peripheral speed and in the directions indicated by their relative arrows, respectively. Furthermore, said pairs of rolls are so timed that their peripheral speed is the same as that of the face of folding-bed 52 on carriage 2. Above shaft 5 and mounted for rotation in side frames 3 is shaft 4. On said shaft 4 is fixed gear 23, meshing with and driven by gear 6. Said gear 6 is in the present instance, for convenience, illustrated as three times the diameter of gear 23. Also carriage 2, fixed to the same shaft 5 as gear 6, is provided with three folding-beds, as 52. Gear 23 and shaft 4 are arranged and adapted to make one revolution during one cycle of the diamond-folding mechanism and carriage 2 and gear 6 to make one revolution for every three cycles of the diamond-folding mechanism. From gear 24 on shaft 4, through gears 25 26, is driven gear 27 on sleeve 29, to which sleeve is affixed side nipper-cam 30. Gears 24 27 being of the same diameter, cam 30 revolves once for every revolution of gears 23 24.

Rolls 21 22 are provided to feed the tucked-paper tubing from the forming mechanism (not shown) and deliver it to the severing mechanism, in this instance illustrated as comprising a serrated knife 31, float 32, and striker 33. Said striker is slidably mounted in T-head 101 of vertical rock-shaft 102, which rock-shaft is mounted for oscillation in bracket 103, projecting outwardly from left-hand frame 3. On the lower end of said rock-shaft is fixed arm 104, on the free end of which arm is revolvably mounted roll 105. On vertical shaft 106, mounted for revolution in brackets 107 108, which brackets project outwardly from left-hand side frame 3, is fixed

cam 109. Said cam is provided with a cam-groove 109^a, disposed and adapted for engagement with roll 105, whereby arm 104 and from it, through rock-shaft 102, T-head 101 may be oscillated. By this means striker 33 may be caused to pass across the serrated edges, respectively, of knife 31 and float 32. Power may be communicated to vertical shaft 106 from shaft 10^a by the following means:

10 Miter-gear 110 on shaft 106 meshes with miter-gear 111, fixed to the outer end of tubular shaft 112. On the inner end of said shaft 112 is fixed spur-gear 113, which gear meshes with idle gear 114, mounted for free revolution 15 on stud 115, which stud is shown as screwed into a suitably-threaded boss on frame 3. Fast to gear 114 and adapted to revolve with it is gear 116, and meshing with gear 116 and fast to shaft 10^a is gear 117. Shaft 10^a revolves only half as fast as it is desired to revolve shaft 106 and gears 117, 116, 114, and 113 are so proportioned as to cause tubular shaft 112, and therefore vertical shaft 106, driven therefrom by miter-gears 111 110, to 20 run twice as fast as shaft 10^a.

To cause striker 33 to slide inwardly and outwardly in T-head 101 and in time with the oscillation of said head and striker, the following means are provided: Near the upper end of shaft 106 and fixed thereto is gear 118, meshing with equal gear 119, fixed to stud 120, which stud is revolubly mounted in extension 103^a of bracket 103. On the upper face of gear 119 is fixed a crank-arm 121 to 30 a post, on the outer end of which arm is pivoted one end of link 122 by means of pin 123. The other end of said link is pivoted by pin 124 to striker 33. Crank-arm 121 is so disposed on gear 119 in relation to cam-path 109^a 35 of cam 109 as to cause, in coaction with the oscillation of T-head 101 on shaft 102, the end 33^a of the operative edge of striker 33 to traverse an approximately rectangular path, as indicated by dot-and-dash line S, Fig. 15.

40 Above and subsequent to the striker are rolls 17 18, which receive the bag-tube from rolls 21 22 and after the bag-blank has been severed from the continuous tube deliver said blank to the folding means. Upper roll 18 is mounted in adjustable boxes 34, which by 45 means of set-screws 35 may be operated to vary the relation of rolls 17 18 to each other, and thereby vary the tension on the bag-blanks as they pass between said rolls.

50 Feed-rolls 17 18 are provided with slackening means comprising coacting vibratable slackers-bars 36 37, respectively. Slacker-bar 36 is supported for vibration by arms 38 39, pivoted on shaft 40 in roll 17. Said slacker-bar 55 is normally held against the forward wall of groove 41 in said roll by means of springs 43 44, and the stroke of said slacker-bar may be limited and adjusted by means of set-screw

60 42, threaded into the rear wall of groove 41. Slacker-bar 37 in roll 18 is mounted and adjusted similarly to bar 36 in roll 17, and the foregoing description of one will answer for both. Slacker-bar 37 is provided with a creaser-blade 45, extending throughout its length, for coaction with creaser-groove 46, extending 65 throughout the length of slacker-bar 36. Also upper roll 18 has a creaser-blade 47 extending throughout its length and parallel with the axis of the roll and with slacker-bar 37 and creaser-blade 45. Said blade is situated 70 in advance of the normal position of blade 45 a peripheral distance equal to the depth of the side tuck of the bag-blank to be operated upon. Roll 17 is provided with a creaser-groove 48, extending throughout its length and situated 75 for coaction with blade 47 in roll 18. The two sets of creasers 45 46 and 47 48, respectively, are so situated with reference to the slackening means that the operation of the latter can have 80 no influence on the relative actions of said 85 creasers, in that slacker-bars 36 37 do not act until creasers 45 46 have operated upon the bag-blank. Therefore any adjustment or variation in the amount of slackening in no way 85 affects the relative positions of the two creasers, or creasers 45 46 would be equally efficient if arranged in their respective rolls subsequent to slacker-bars 36 37 instead of in advance thereof, and thereby be arranged and adapted to crease the bag-blank after it is severed from the continuous tube instead of previous to such severing, as shown in Fig. 4. Feed-rolls 17 18 have their peripheries cut 90 away in the usual manner to prevent their crushing the folds of the tucked-paper tube; but for a short distance on each side of creaser-blade 47 and groove 48, Fig. 4, the surface of the rolls is continuously of maximum diameter throughout the length thereof, so that the bag-blank may be creased uniformly throughout its width. The faces 50 51 of slacker-bars 95 36 37, respectively, are adapted for coaction 100 throughout their length, and creasers 45 46 are thereby adapted to form a uniform crease 105 throughout the width of the bag-blank.

110 The means provided for opening out the forward end of the bag-blank and folding it down into the diamond form is as follows: On carriage 2, mounted for continuous revolution on shaft 5, may be mounted one or 115 more folding-beds, (in the present instance three are shown,) as 52, each having the usual front clip 53 and bevel-edged side clips 54. Front clip 53 is pivotally mounted in the carriage at 55 and is provided with an inwardly-extending arm 56. Said arm may be provided with a cam-roll, as 57, for engagement with cam 58. The front clips, respectively, of the other folding-beds are arranged, mounted, and actuated similarly to clip 53. Side 120 clips 54 are adjustably held in pivotally-

mounted arms 91 on opposite sides of folding-bed 52. Said arms 91 extend downwardly beyond their pivotal points and are provided with rolls, as 92, for engagement with actuating-cams, (not shown,) but which cams and their operation are well known in the art and may be found illustrated and described, for instance, in United States Patent to Claussen and Mortson, No. 635,090, dated October 17, 1899. Mounted for oscillation on fixed trunnions 59 above and adjacent to carrier 2 is a gripper-carrier, (indicated in a general way by 60.) Said gripper-carrier comprises a frame 61 of any suitable shape, in the present instance illustrated as of yoke shape, for carrying the several parts of the mechanism. On the inner ends, respectively, of shafts 62 63, which shafts are disposed opposite to each other and at substantially forty-five degrees to the axis of oscillation of carrier 60, are side clips 64 65, respectively. On the outer ends of said shafts are segment-gears 66 67, respectively, meshing with other segment-gears 68 69, respectively. Segment-gears 68 69 are fast to shaft 70, which shaft is mounted in bearings in gripper-carrier 60. On the left-hand end of shaft 70, Fig. 5, is fixed arm 71, on the outer end of which is mounted cam-roll 72 for coaction with cam 30. Said cam 30 comprises two relatively adjustable disk-like parts or members, as 301 and 302, the former having a hub 303, which may be clamped to sleeve 29 of gear 27 and adjusted thereon by means of clamp-screw 304. Said cam part 301 is provided with one or more slots, as 305, through which clamp-screws 306 pass for engagement with cam part 302 for clamping the same to cam part 301. Cam part 302 may thereby be adjusted relative to cam part 301. Said cam 30 is coaxial with trunnion-shaft 59 of gripper-carrier 60 and may be caused to revolve at a uniform speed in a clockwise direction, Fig. 6, by means already herein described. Roll 72 is constantly urged toward the periphery of cam 30 by means of spring 73, one end of which spring bears upon the face of frame 61 and the other end is held in collar 74, adjustably secured to shaft 70 by means of set-screw 76. Fast to yoke-frame 61 and projecting inwardly therefrom are spring-fingers 78 79, which fingers are so positioned laterally with respect to the path of the bag-blank as to enable them to coact with side clips 64 65, respectively, to grip the upper plies of the side tucks of the bag-blank, respectively, in the operation of forming the bag-bottom. Yoke-frame 61 is provided with a front finger 77 for entering the mouth of the bag-blank to assist in turning back the upper ply thereof.

Oscillatory motion may be imparted to gripper-carrier 60 by the following means: Suitably mounted for oscillation at 81 in the

upper part of one of frames 3 is an arm 82, having at its lower end a toothed segment 84, 65 arranged and adapted to mesh with gear 75 on gripper-carrier trunnion-shaft 59. On arm 82, intermediate toothed segment 84 thereof, and pivot-shaft 81 is mounted roll 83 for engagement with cam-slot 80^a of cam 80, whereby upon the revolution of cam 80 said gripper-carrier may be oscillated through a predetermined stroke.

The operation of my improved machine is as follows: Suitable tucked-paper tubing having slits 86 at proper intervals therein having been fed into proper position under serrated knife 31 and around float 32 between feed-rolls 21 22, power is applied and the machine set in motion. By means of rolls 21 22 the tube 80 is fed upwardly into engagement with rolls 17 18, revolving at the same surface speed as rolls 21 22, and said tube is held taut between the two pairs of rolls, respectively. Continuing the upward movement of the bag-tube 85 between rolls 17 18, said tube presently engages with creaser 47 48, blade 47 in roll 18 forcing said tube into groove 48 in roll 17, thereby forming a crease 87 entirely across the bag-tube and at right angles to the length 90 thereof. Said tube still continuing its upward movement presently passes into engagement with slacker-bars 36 37. Said slacker-bars being provided with creasers 45 46, a second crease 88 is formed across the blank similar to crease 87 and at a predetermined distance therefrom equal to the depth of either of the side tucks. During this time striker 33 has moved forward in the direction indicated by arrow e, Fig. 15, into contact with the bag-tube and continuing its movement across the path thereof pushes said tube over the edges of knife 31 and float 32. This backward pulling on the advanced portion of the bag-tube causes the slacker-bars 36 37, between which said tube is gripped, to swing backwardly on their trunnions until they contact with their respective stop-screws, when the bag-blank is severed from the continuous tube and the slacker-bars, by means of springs 110 provided therefor, are returned to their normal positions, respectively, carrying the bag-blank with them and restoring said blank to its previous and normal position in relation to the machine. During the operation of the 115 slacker-bars rolls 17 18 have continued their uniform rotary movement and immediately regrip the severed and creased bag-blank 90 between their coacting peripheries, respectively, and feed said blank onward and upward onto folding-bed 52 of cylinder 2. As the mouth of the bag-blank stands normally more or less open, entrance is provided therein for finger 77 of the gripper-carrier and front clip 53 of the folding-bed. Said front clip thereupon 120 grips the forward end of the lower ply of the

bag-blank to the folding-bed, Figs. 5 and 6. Side clips 54 on said folding-bed 52 now swing inwardly on their trunnions and enter the side tucks, respectively, of the blank and clamp the 5 lower plies thereof down to the face of the folding-bed. During the feeding of the bag-blank onto the revoluble folding-bed the revolution of cam 30 has presented rise 30^a to roll 72, and thereby oscillated arm 71 and, through shaft 10 70, segment-gears 68 69 and 66 67, shafts 62 63, and side clips 64 65, respectively, until when the bag-blank is gripped to the folding-bed by front clip 53 said side clips have entered the side tucks, respectively, of the bag-blank 15 and are ready to grip the upper plies thereof to spring-fingers 78 79, respectively. (See Figs. 5 and 6.) Folding-bed 52 continues its rotation on carrier 2 about axis 5, and the bag-blank is led well up onto front hook 77 of gripper-carrier 60. Said gripper-carrier, by means of cam 80, roll 83, arm 82, segment 84 thereon, and gear 27, now commences to rotate in an anti-clockwise direction, and cam 30 continues its rotation in a clockwise direction. 20 This very soon brings roll 72 onto the high part 30^b of cam 30, Figs. 7 and 8, causing side clips 64 65 to grip the upper plies of the side tucks, respectively, to spring-fingers 78 79. The bag-blank is now fully in the grasp of the 25 several clips, and folding-bed 52 continuing its onward movement about axis 5 and gripper-carrier 60 continuing its anti-clockwise turning about trunnion-shaft 70 the mouth of the bag-blank is opened out and folded down into 30 the diamond form, the lateral edges 93 94 of the bag-bottom being readily folded along the lines defined by creaser 47 48, as hereinbefore described. Also the creases formed at the same time and by the same means in the other plies 35 of the blank now coincide with creases 97 98, made by the original folding of the tucks in the tubing, and thus facilitate the ease and accuracy in the later folding of the end flaps of the bag-bottom. When gripper-carrier 60 40 has traveled nearly to the end of its rearward stroke in an anti-clockwise direction, roll 72 on arm 71 is met by the low part 30^c of cam 30, traveling in a clockwise direction, and descends onto said low part, thereby causing 45 side clips 78 79 to open and liberate the diamond-folded bag-blank, Figs. 9 and 10. Gripper-carrier 60 continues its rearward stroke and folding-bed 52 its forward movement, and front clip 53 releases front flap 95 of the bag-blank, which is therefore allowed to spring 50 up from folding-bed 52, ready to be folded over onto the bag-bottom, Figs. 11 and 12. Side clips 54 hold the bag-blank to folding-bed 52 until rear flap 96 of the bag-blank is 55 withdrawn from front hook 77 and the partially-completed bag delivered to some suitable mechanism (not shown) for folding and pasting the end flaps. Gripper-carrier 60 re-

mains at rest in its rearward position, Figs. 65 11 and 12, to allow the bag-blank to be removed therefrom, as just described, and in the meantime cam 30 has continued its uniform rotation in a clockwise direction. Gripper-carrier 60 now starts on its return movement, also in a clockwise direction, but travels more rapidly than cam 30, whereby roll 72 on arm 71 mounts rise 30^a on cam 30, thereby causing the partial closing of side clips 64 65 on gripper-carrier 60. However, said gripper-carrier still continuing its return movement at a speed in excess of the speed of cam 30 said roll 72 runs down from rise 30^a and onto low part 30^c of said cam, thereby causing side clips 64 65 to again open. The gripper-carrier has now reached its forward position and 80 is ready for the receipt of another bag-blank, Figs. 13 and 14.

The partial closing and reopening of side clips 64 65 during the return movement of the gripper-carrier is not necessary to the functional operation of the machine, but is in no way detrimental thereto. Said partial closing and reopening of said clips is the result of the unusual length of cam time provided for the operative closing of said side clips, which 90 length of time is of great value, contributing in a marked degree to accuracy in forming the diamond and to the speed at which the machine may be successfully operated.

I claim—

1. The combination of a pair of rolls 17, 18, a creaser-blade 47 in one of the rolls, and a creaser-groove 48 in the other roll, a slacker-bar in each of said rolls, means for supporting each slacker-bar to yield in the line of its travel, a creaser-blade 45 in one of the slacker-bars, and a creaser-groove 46 in the other slacker-bar; all combined and operating together substantially as described.

2. The combination of a pair of rolls 17, 18, a creaser-blade 47 in one of the rolls, and a creaser-groove 48 in the other roll, a slacker-bar in each of said rolls, means for supporting each slacker-bar to yield in the line of its travel, means to adjust the strokes respectively 110 of the slacker-bars, a creaser-blade 45 in one of the slacker-bars, and a creaser-groove 46 in the other slacker-bar; all combined and operating together substantially as described.

3. The combination of a pair of rolls 17, 18, a creaser-blade 47 in one of the rolls, and a creaser-groove 48 in the other roll, slacker-bars 36, 37 in said rolls, respectively, means for pivotally supporting each slacker-bar to yield in the direction of its travel, a creaser-blade 45 in one of the slacker-bars, and a creaser-groove 46 in the other slacker-bar; all combined and operating together substantially as described.

4. In a paper-bag machine, the combination 125 of a pair of rolls 17, 18, a creaser-blade 47 in

one of the rolls, and a creaser-groove 48 in the other roll, a slacker-bar in each of said rolls, means for supporting each slacker-bar to yield in the line of its travel, a creaser-blade 45 in 5 one of the slacker-bars, and a creaser-groove 46 in the other slacker-bar, a folding-bed 52, having side clips 54 thereon, an oscillating gripper-carrier 60, fingers 78, 79, and side clips 64, 65 thereon, a cam 30 for closing side clips 10 64, 65, and means to close said side clips from

said cam; all combined and operating together substantially as described.

In testimony whereof I have signed my name to this specification, in the presence of two subscribing witnesses, this 11th day of April, 1904.

FREDERICK E. STRASBURG.
